UNITED STATES PATENT OFFICE.

SATTERLEE ARNOLD, OF MORRISTOWN, NEW JERSEY, ASSIGNOR TO
ANNA M. ARNOLD, OF BROOKLYN, NEW YORK.

SEWING-MACHINE.

No. 829,937.

Specification of Letters Patent.

Patented Aug. 28, 1906.

Application filed July 26, 1889. Serial No. 318,646.

To all whom it may concern:

Be it known that I, SATTERLEE ARNOLD, a citizen of the United States, residing at Morristown, in the county of Morris and State of New Jersey, have invented certain new and useful Improvements in Sewing-Machines, of which the following is a specification, reference being had therein to the accompanying drawings.

10 My invention relates to a sewing-machine more particularly intended for joining the edges of knit fabrics in the manufacture of stockings and other articles of underwear, but adapted also for ornamental stitching or plain work.

The present invention has been made by me in connection with machines such as shown in my Patents Nos. 311,106, 311,107, and 378,645; and the invention will be illustrated and described in connection with such a machine, although it will be understood that the features forming the invention may be used also in machines of other classes.

The improvements forming the present invention relate more particularly to the feeding and presser-foot mechanisms; to the mechanism for swinging the needle laterally or across the line of the feed; to means for guiding the work to a stitch-forming mechanism, means for presenting the work to a stitch-forming mechanism in such a way as to form a flat seam with a certain looseness of the stiches so that the seam will have any desired degree of softness; to the form of the work-supporting horn, and to means for taking up the wear of the fulcrum-pivot of the looper-rod, all as will hereinafter more fully appear.

In the drawings, Figures 1 and 2 are opposite side elevations, partly broken out, of my improved machine. Fig. 3 is a top view, and Fig. 4 a front end view, of the same. Figs. 5, 6, and 7 are detail views of the presser-foot. Fig. 8 is a detail plan view of the forward end of the work-supporting arm or horn, showing the throat-plate and divider or separator. Fig. 9 is a cross-section through the arm or horn on line 9 9, Fig. 1, with the top plate of said arm or horn omitted. Fig. 10 is a plan view of the feeding-foot. Figs. 11, 12, 13, and 13^a are detail views of the throat-plate. Fig. 14 is a detail view of the vertical divider or separator and guide. Fig. 15 is an enlarged section of the throat-plate and tongue

of the divider, illustrating the operation of the latter; and Figs. 16, 17, and 18 are diagrams illustrating different seams.

A denotes the bracket-arm of the machine, to the rear portion of which is journaled the vertical driving-shaft B, having at its lower end a crank-disk b, connected by a link b' with the upper crank b² of the vertical hook-rod shaft B', arranged out of line with the shaft B, so as to receive a variable rotary movement from the latter, and having at its lower end the crank b³, connected with the looper-rod C, provided at its forward end with the looper c to carry the needle-thread around the stationary shuttle c'. The primary and secondary needle-bar-operating levers a a', which are connected together and to the needle-bar a² by links a³, are operated from the eccentric a⁴ on the shaft B through the pitman a⁵. The needle-bar is reciprocated vertically in a horizontally-swinging frame E, pivoted on center screws a⁶ in the bracket-arm A. The shaft B is provided with a driving-pulley B² and with a worm B³, meshing with a worm-wheel D, secured to a shaft D', journaled in bearings in a bracket A', attached to the arm A.

The parts thus far described are or may be substantially the same as in my patents hereinbefore referred to, but in which the swinging movements of the needle-bar frame to move the needles laterally or horizontally were not positive in both directions, as is necessary for accurate work, particularly at high rates of speed.

In my improved machine the swinging needle-bar frame E is moved positively back and forth by being connected by a link e with the arm e' on the forward end of a rock-shaft e², journaled in the brackets a' on the arm A and provided at its rear end with an arm e³, having a roller stud or truck entering a cam-groove d in the forward face of the wheel D. The arm e' is provided with a curved slot e⁴, in which the stud e⁵, connecting the link e with said arm, is adjustably secured, and the amount of throw given to the swinging needle-bar frame may be varied at pleasure without changing its central position by adjusting said stud nearer to or farther from the rock-shaft e² in the said curved slot, the set-nut e⁶ on the said stud having an arm e⁷ for convenience of ready adjustment of the stud.

To provide for adjustment of the position

of the swinging needle-bar frame E laterally without changing its throw, the said swinging frame has an adjustable connection with the link *e*, formed in the present instance by 5 the bolt *e*⁸, having a hole through its head to receive the screw stud or bolt *e*⁹, passing through the end of a link *e* nearest said frame, the shank of said bolt *e*⁸ passing through a lug or projection *e*¹¹ on the said frame and being threaded for the reception of the jam-nuts *e*¹², the positions of which may be changed to vary the lateral position of the said swinging needle-bar frame. The bolts or studs at the opposite ends of the link *e* 15 have universal-joint connections therewith to prevent the connected parts vibrating in different planes from binding.

The feeding of the work is effected by an upper step-feed or feeding-foot *f*, carried by 20 a feed-bar F, pivoted near its top on the screw *f*¹, passing through the slot *f*², said feed-bar having a lug or projection *f*³ for the engagement of a lifting cam-lever *f*⁴.

In introducing the work beneath the feeding-foot it is desirable that the said foot be held about the thickness of the fabric above the work-plate, so that when one piece of fabric is adjusted beneath the feeding-foot it will be frictionally held by the latter, while 25 the operator is free to use both hands to adjust the other piece of fabric and to start the sewing, the two pieces of fabric in making the seams for which my improved machine is more particularly intended being laid flatwise edge to edge on the work-plate. To hold the feeding-foot in any position of vertical adjustment, I provide one or more spring-washers *f*¹¹, placed against the said lifting-lever *f*⁴ beneath the head of the screw *f*¹², on 30 which said lever is pivoted, the frictional contact between said washer or washers and said lever and screw-head serving to retain the said lever in any position to which it may be moved in lifting the feeding-foot.

45 The feed-bar F is connected near its lower end by a link *g* to the vertical arm *g*¹ of a bell-crank feed-operating lever, the longer horizontal or regulating arm *g*² of which is slotted for the reception of an adjustable stud *g*³ on 50 the lower end of a link *g*⁴, which is attached at its upper end to an arm *h* of a rock-shaft or rocker H, made in the present instance in the form of a sleeve surrounding the feed-bar-lifting shaft I, which is journaled in bearings 55 in the brackets *a*⁷, said rock-shaft H having a second arm *h*¹, provided with a roller-stud entering the cam-groove *d*¹ in the forward face of the cam-wheel D² on the shaft D¹, which latter, as it carries the cam-wheel D², 60 which operates the feed, may be termed the "feeding-shaft." The feed-bar-lifting rock-shaft I has at its forward end an arm *i* to engage an adjustable screw *f*⁶, tapped in the lug *f*⁸ on the feed-bar F, said shaft I having 65 at its rear end a second arm *i*¹, bearing a

roller-stud entering the cam-groove *d*² in the rear face of the cam-wheel D¹. By changing the position of the adjustable stud *g*³ in the slot of the regulating-arm *g*² nearer to or farther from the fulcrum of the feed-operating bell-crank lever the horizontal throw of the feeding-foot may be varied; said stud having on its inner end a nut provided with a lever or handle *g*⁵, by which it may be easily loosened or tightened.

The feeding-foot *f* is yieldingly pressed upon the work by a spring *f*⁷, attached at its upper end to an arm *f*⁸, secured to the feed-bar by a screw *f*⁹, said spring *f*⁷ being attached at its lower end to the bell-crank lever 80 or other suitable relatively stationary part, and its tension may be adjusted by loosening the screw *f*⁹ and then raising or lowering the outer end of the arm (which turns on the screw *f*⁹ as a pivot) and then again tightening said screw. In this way the pressure of the feeding-foot on the work may be varied for different kinds of work or thicknesses of fabric. The adjustable screw *f*⁵, against which the arm *i* of the rock-shaft I impinges, 90 also permits the vertical throw or lift of the feed-bar (and which occurs when the return or non-feeding horizontal movement of the said bar is to take place) to be varied for work of different thicknesses.

J is the presser-foot, having an opening for the reception of the feeding-foot *f* and being carried by a presser-bar K, surrounded by a spiral spring *k*, which holds down the presser-foot; but in sewing knit fabrics on my improved machine it is not desirable that the full pressure of the presser-foot should be received by the work; but, on the contrary, it is better that the presser-foot should be held a distance above the work-plate about equal 100 to the thickness of the fabric when the latter is slightly compressed, and the presser-foot when thus supported at an interval above the work-plate serves with the latter as an uncurling device to smooth out the curled 110 edges of the knit goods, so that they can be accurately presented to the stitch-forming mechanism. To this end the presser-bar K is provided with a stop to engage some part 115 above the work-plate, and thus hold the said presser-foot slightly above the latter. In the present instance this presser-foot stop is secured by providing the presser-bar at its upper end with an arm *k*¹, through which is tapped a screw *k*², forming a projection to 120 engage a lifting-arm *m* on the forward end of the presser-foot, lifting rock-shaft M, the latter being journaled in the brackets *a*⁷ and having at its rear end a second arm *m*¹, provided with a roller stud or truck entering the 125 cam-groove *d*⁴ in the rear face of the wheel D. The rock-shaft M is moved at the proper intervals to cause its arm *m* to lift the presser-foot entirely clear of the work when the movements of the feeding-foot *f* occur, the 130

said arms at other times serving (in connection with the said screw k^2) as a stop against which the said screw abuts to hold the presser-foot slightly above the work-plate 5 for the purpose above stated. For convenience of adjustment the screw k is provided with a small crank-handle k^4 , by which it may be turned, and it is held in any position desired by the set-nut k^3 .

From the foregoing it will be apparent that the lateral movements of the needle-bar, the back and forth and lifting movements of the feeding-foot, and the lifting movements of the presser-foot, are all derived from the 10 worm-wheel D and worm B³, and by providing interchangeable worms and worm-wheels so geared that the worm-wheel will rotate once to each four, six, or any other desired number of revolutions of the worm and 15 of the main shaft, by which the latter is carried and which reciprocates the needle-bar vertically at each revolution, and also by varying the shapes of the cam-grooves in the said interchangeable worm-wheels D, and by 20 providing interchangeable feed-operating wheels or disks D², having cam-grooves of different shapes in their opposite sides, I am enabled to form a great variety of stitches adapted for ornamenting fabrics or for uniting 25 the edges thereof. Thus if it be desired to sew what may be termed a "gathering-tie" or "Egyptian stitch-seam," as represented in Fig. 16, to join by a flat seam the meeting edges of two pieces of fabric lying in the 30 same horizontal plane the needle is first caused to descend on one side of the meeting edges, and then, without feeding the work, the needle is moved laterally straight across said edges and forms a stitch on the other 35 side thereof, and then, without swinging the needle laterally, the work is fed the length of a stitch, so that the needle forms another stitch on the same side of the edges as the last stitch, and at the next stitch the feed 40 rests and the needle swings laterally straight across the edges and descends through the fabric on the first side of said edges, the operation continuing in this way, the swinging or lateral movements of the needle and the 45 feeding movements being intermittent with each other, or being made at alternate 50 stitches, to form the seam referred to.

With a lock-stitch seam made by single upper and lower threads the seam is alike so 55 far as the arrangement of the two threads is concerned on both sides of the work, and as with my stationary shuttle I can use a soft or loosely-twisted lower thread or yarn which will form a soft seam I am enabled with my im- 60 proved machine to unite the edges of stockings and other knit goods by a soft flat seam having the appearance and being in all respects fully equal to the hand-made seams heretofore almost universally employed in 65 all of the better classes of hosiery, and par-

ticularly with all fine goods. Thus in making the gathering-tie or Egyptian seam above described with the stitches close together in the direction of the length of the seam and with a rather large soft yarn in the shuttle 70 the seam has the appearance on the shuttle side of the work (which is the fair or outside when the work is finished) represented by Fig. 17, the threads crossing the meeting edges at right angles thereto, or approxi- 75 mately so, thus simulating the appearance of handwork, and as each crossing stitch has a "double grip" or a hold at two points in the fabric, afforded by the straight-ahead or gathering grip or tie-strokes between the 80 crossing stitches, the seam is really stronger than the hand-seam. To secure sufficient looseness to prevent the seams of closely-placed stitches from being hard or puckered, the adjacent edges of the fabrics may be held 85 slightly separated when sewing, or the needle-thread may be laid over a small stitch-holding finger to prevent the stitches from being drawn too tight by the pull of the take-up, or both of these devices (to be fully de- 90 scribed presently) may be employed.

In addition to the seam above described it will be obvious that many other ornamental and useful seams may be formed on my improved machine by varying the shapes of the 95 cams from which the feeding-foot and swinging needle-bar frame are operated or by disconnecting the said frame from its operating rock-shaft. Thus by giving the needle-bar frame and needle-bar a regular back- 100 and - forth - swinging movement at each stitch and by giving the feed a regular movement so as to feed at each stitch an ordinary zigzag or herring-bone-stitch seam (see Fig. 18) may be formed, and by disconnecting the link e from the needle-bar frame and using a regular feed a plain straight-ahead-stitch seam will be produced. With the needle-bar frame disconnected from its operating rock-shaft and the feed operated to 105 give the work alternate long forward and short backward movements a back-stitch seam—such as is described in my Patent No. 378,644, February 28, 1888—will be the result, and by different combinations of the 110 feed and swinging needle what are known as the "vine" or "crossing" stitch and many other ornamental stitch-seams may be made.

The looper-rod C, operated from the variably-rotating shaft B' (to give a rapid move- 115 ment to the looper c when the latter is taking the needle-thread and a slower movement at other times, as described in my Patents Nos. 331,106 and 331,107, hereinbefore men- 120 tioned) is in the present instance provided 125 near its middle with side flanges c², embrac- ing a guide-block c³, pivoted on a conical or tapered stud c⁴, the shank of which is tapped in a bridge-piece A², screwed to the sides of the hollow work-supporting arm or horn A⁴, 130

a check-nut c^5 on the threaded shank of said stud serving to hold the latter securely in any position to which it may be adjusted by a screw-driver inserted in the slot or nick at 5 the upper end of said shank. In operation the looper-rod has an endwise or longitudinal movement and a lateral or swinging movement, the latter movement being provided for by the stud c^4 , on which the block c^3 can 10 swing, the said block, in connection with the flanges on the looper-rod, serving to guide said rod in its lengthwise movements. The said flanges are made slightly flaring, and the said block is tapered transversely (see Fig. 9) 15 to fit between them, and as the conical stud is made adjustable it is obvious that all wear of these parts may be readily taken up.

The take-up which I prefer to use consists of the oppositely operating and connected 20 take-up levers N , receiving their movements from the grooved cam B^4 in the crank-disk b on the shaft B through the rocker N' , having a roller-stud n , entering the groove of said cam and a pitman L , connecting said rocker 25 with said take-up levers. The presser-foot J extends in front of the needle and is provided with an opening j to receive the feeding-foot f , the latter being preferably provided with two narrow wings o , extending in 30 front of the needle (when the feeding-foot is in a forward position toward the operator or the front end of the machine) into the notches or recesses j' in the presser-foot, the latter having also the notches j^2 to receive the 35 needle in its different lateral positions. The feeding-foot has a solid rear or heel portion bearing on the work rearward of the needle hole or slot in the throat-plate, and thus, in 40 co-operation with the presser-foot, said feeding-foot will prevent the work from being thrust down into said hole or slot by the needle, a difficulty occurring more or less with the wheel-feed machine shown by my Patent No. 331,106 and resulting in more or 45 less roughness of seam. As hereinbefore described, the presser-foot is supported so as to be slightly above the work-plate, so that it will have but a slight frictional contact with the work, and it thus serves as part of a 50 smoothing or uncurling device to smooth out the edges of knitted fabrics, and to perform its function properly in this respect its front end is cut out to form a **U** or **V** shaped or tapering opening or recess the apex of which is rearward toward the needle, the walls of 55 said recess being preferably beveled slightly, as shown in the detail views Figs. 6 and 7, at obtuse angles, so that the lower or scraping edges will prevent any curled fabrics from 60 passing beneath the presser-foot until pressed out in a smooth condition.

P is the throat-plate, which is also provided with a **U** or **V** shaped or tapering opening or recess in front of the needle and also preferably having beveled rear walls, as shown in

Fig. 13, to coöperate with the slightly-lifted presser-foot in uncurling the fabrics. These beveled rear walls make scraping edges at their upper corners p^2 to uncurl the knit fabrics. This scraping action would measurably be effected if the said rear walls were vertical instead of beveled if the corners p^2 were square. The throat-plate is provided with a rearwardly-pointing tongue p , at the sides of which are the notches p^3 , into which the needle descends and rearward of which is an opening p' to permit the stitches laid over said tongue to escape therefrom. At the rear of said opening the upper surface of said plate is beveled or chamfered, as shown at p^4 , 75 Figs. 11 and 12, to permit the rather loose stitches on the lower side of the work to ride up easily without catching. The opening p' is inclosed by leaving the throat-plate rearward thereof intact, so as to form a bearing-surface, which is level or even with the rest of the top of the said plate immediately rearward of said opening, said bearing-surface receiving the pressure of the feeding-foot, so that the work will be held at all times securely and accurately. 85

The throat-plate is removably attached to the work-plate, (in the present instance by the eccentric-headed screw r' , which holds the flanged or undercut throat-plate in a recess in the work-plate,) so that interchangeable throat-plates having tongues p of different widths to accommodate different lateral throws of the swinging needle may be employed, the lateral throws of the needle being necessarily greater with heavier fabrics than with the finer or lighter ones. 95

The throat-plate P is preferably provided on its under side with a cross-bar p^5 , which is below the tongue p , between the points where the needle descends and the rear end of the said tongue, or, if the tongue be rather short, as shown in Fig. 13^a, (which is a bottom view of a throat-plate having a **V**-shaped rearwardly-tapering opening or recess,) said cross-bar is about even with the end of said tongue, and as the latter is thinner than the body of the throat-plate (see Fig. 12) there is sufficient space for the thread or stitches to pass between the lower side of said tongue and the upper side of said bar. The purpose of the bar p^5 is to hold the lower or bobbin thread in the right position, so that when forming seams, as shown in Figs. 16 and 17, the cross or "cable-laid" stitches will be placed with evenness and regularity on the under (or fair) side of the work. 115

My improved machine is more especially intended for uniting two fabric edges placed flatwise or edge to edge, although it may obviously be used for covering seams or for various other purposes, and to even and guide the fabric edges properly to the needle I employ a vertically-placed guiding divider or separator R, arranged in front of the presser- 125 130

foot and preferably having a tongue *r* extending beneath the presser-foot and rearwardly past the needle or sewing-point. In uniting knit fabrics edge to edge it is necessary in order to secure a soft seam (particularly when the stitches are made rather fine or close together) that the fabric edges should be slightly separated at the sewing-point to leave a slight interval or space between said edges when united to provide for shrinkage in scouring or when the fabrics are washed after being sewed; otherwise they are liable to pucker or the seams will be hard, and this separation of the fabrics at the sewing-point is secured by the guiding and separating tongue *r*, which is preferably square or rectangular in cross-section, or at least it must have vertical sides to guide the fabric edges and hold them separated.

The enlarged sectional diagram, Fig. 15, taken on line 15 15, Fig. 8, illustrates the operation of the separator, *s* denoting sections of fabric in contact with the vertical sides of the separating-tongue *r*, and dotted lines *t* denoting the planes of the descent of the needle on the opposite sides of the tongue *p* of the throat-plate *P*, the dotted lines above the tongue *r* denoting the part of the guiding divider or separator *R* which comes in front of the said tongue. Instead of making the tongue *r* a part of the vertical divider or separator it may be a part of the presser-foot, as denoted by the dotted lines in Figs. 6 and 7; but when a part of the guiding divider or separator it will extend beneath the forward end of the presser-foot. The guiding divider or separator is preferably removable from its operative position to provide for easy removal or insertion of the work and is shown in the present instance as being pivoted on its attaching-screw *r*² so that it may be turned down out of the way to the position shown in dotted lines in Fig. 1 when desired.

The hollow work-supporting arm or horn *A*⁴ is truncated at its forward end or has rounded corners with a straight part between them. As the feeding or stitch forming and feeding devices are arranged close to the end of this arm or horn and as the feeding device or foot is arranged to move lengthwise of the latter to feed the work longitudinally thereof, the machine is particularly adapted for sewing the angular seams in the heel portions of stockings and also the toe portions thereof, as well as for sewing mitts, gloves, or other tubular articles, particularly where flat, neat, and fine seams with stitches close to the edges to be united are required.

In the operation of my machine in sewing flat seams the fabric edges are abutted against the guiding divider or separator and adjusted beneath the forward end of the presser and feeding feet. The machine is then started and the needle, which recipro-

cates or moves horizontally or laterally crosswise of the arm or horn above the latter, as will be apparent, descends first into one part of the fabric and then into the other, crossing and recrossing the edges in any desired order of the stitches as the work is moved along by the feed, and as the work thus progresses the edges thereof are smoothed out and pressed against the guiding divider or separator, which, in connection with the separating-tongue *r*, guides them properly to the stitch-forming mechanism, while holding them slightly apart to secure proper softness of the seam. The tongue on the throat-plate over which the two threads of the seam are laid serves as a resistance to the take-up and prevents the latter from drawing the stitches so tight as to make the seam hard or create a liability of puckering when the stitches are close together.

As stated above, the tongue *r* is preferably used in uniting knit fabrics edge to edge, particularly when the stitches are fine or close together, so as to separate the fabric edges sufficiently to secure a soft seam, as described, and when the fabric edges are to be thus secured together and the tongue *r* used for separating them the portion of the divider or separator *R* which lies in front of the needle will preferably be of the same width as that portion which extends across and behind the path of the needle, so that the fabric edges when placed against the portion of the divider or separator in front of the needle will be separated to the same extent as in passing the needle and be guided in parallel lines to the latter. The width of the tongue *r* will obviously depend upon the distance which it is desired to separate the edges of the fabrics, and this width of the tongue *r* when the latter is used will preferably determine also the width of the portion of the divider and separator in front of the needle, although this is not absolutely essential. The tongue *r* is used when a soft seam is to be produced for the purpose of leaving the slight interval or space desirable for forming a soft seam, and it is obvious that the thickness of the dividing guider or separator in front of the sewing-point depends upon the position desired for the fabric edges, this member *R* performing the function of a guide which by entering between or dividing the fabric edges secures the guiding of the fabrics correctly to the stitch-forming mechanism, and whatever be the position of these edges relatively to each other this guide will preferably be formed so as to secure as nearly as possible the movement of the edges past the sewing-point in lines parallel to each other, as in the construction illustrated in the drawings, for which purpose this guide must obviously be made as thin as possible consistently with the re-

quired rigidity and the proper positioning of the edges. If this guide be used in uniting two pieces of fabric, the opposite edges will be brought up on opposite sides and 5 abutted with the guide between them, and thus passed to the stitch-forming mechanism, while if the machine be used for covering seams already formed between two pieces of fabric the fabrics will be placed in 10 position with the divider entering the seam slightly between the two pieces of fabric, and thus passed to the stitch-forming mechanism. The length of the guiding divider or separator in front of the stitch-forming mechanism may be varied, and the length preferred will depend somewhat upon the length 15 of the presser-foot. The greater the length of the divider or separator the more efficient is its guiding action, and for the best results 20 it should extend from approximately the front edge of the presser-foot to the stitch-line, so that the work may be positioned by the forward end of this guide before the work is subjected fully to the pressure of 25 the presser-foot and then be guided and held against sidewise deflection until the sewing is effected. In any case the guiding divider or separator must be of sufficient length to hold the work against sidewise deflection as it moves to the needle, and for 30 this purpose its dimension in front of the needle must be greater longitudinally of the seam than transversely thereto.

I claim—

35 1. In a sewing-machine, the combination with a hollow work-supporting arm or horn, of a throat-plate having a needle-hole, a feeding-foot arranged above the said arm or horn and movable longitudinally thereof, said feeding-foot having a heel portion bearing on the work rearward of the said needle-hole, operating mechanism for said feeding-foot, a co-operating presser-foot, and a stitch-forming mechanism comprising a needle movable horizontally crosswise of said horn, above the latter, and complementary stitch-forming devices within said horn.

50 2. In a sewing-machine, the combination with a hollow work-supporting horn or arm, of a throat-plate having a needle-hole, a feeding-foot arranged above the said arm or horn and movable longitudinally thereof, said feeding-foot having a heel portion bearing on the work rearward of the said needle-hole, operating mechanism for said feeding-foot, a co-operating presser-foot, and a stitch-forming mechanism comprising a needle movable horizontally crosswise of said horn above the latter, and a stationary shuttle and rotating 55 looper both within said horn.

60 3. In a sewing-machine the combination with a hollow work-supporting horn, of a throat-plate having a needle-hole, a feeding-foot arranged above the said horn and mov-

able longitudinally thereof, said feeding-foot 65 having a solid heel portion to bear on the work rearward of said needle-hole, a swinging feed-bar by which said foot is carried, a co-operating presser-foot, a stitch-forming mechanism comprising a needle movable laterally crosswise of said horn, above the latter, and complementary stitch-forming devices within said horn, a driving-shaft from which 70 said stitch-forming mechanism is operated, a feed-shaft geared to said driving-shaft, two cams on said feed-shaft, and connections between said cams and feed-bar whereby horizontal and vertical movements are imparted 75 to the latter.

4. In a sewing-machine, the combination 80 with the work-plate, of a feeding-foot arranged above said work-plate, a swinging feed-bar by which said foot is carried, a driving-shaft, a needle-bar operated from the said shaft, a feed-shaft geared to said driving- 85 shaft, two cams on the said feed-shaft, two rock-shafts, operated by said cams, and connections between said rock-shafts and feed-bar whereby the latter is operated.

5. In a sewing-machine, the combination 90 with the feed-bar F, of the feed-operating bell-crank lever connected with said feed-bar and having a regulating-arm, the rotating cam-wheel D², the feed-operating rock-shaft or rocker II having two arms, one engaging 95 said cam-wheel, and a link g⁴ connected at one end to the other of said arms and being at its opposite end adjustably attached to the said regulating-arm of the said feed-operating lever.

6. In a sewing-machine, the combination with a swinging feed-bar arranged above the work-plate, of a feed-operating rock-shaft or rocker and a feed-lifting rock-shaft both of which are operatively connected with said 105 feed-bar, and rotating cams to operate said rock-shafts.

7. In a sewing-machine, the combination with a swinging feed-bar arranged above the work-plate, of a feed-operating rock-shaft or 110 rocker having two arms, a rotating cam by which one of said arms is engaged, a bell-crank feed-operating lever connected with said feed-bar and having a regulating-arm, a link connecting said regulating-arm with the 115 other arm of said rock-shaft or rocker, a feed-lifting rock-shaft having two arms the forward one of which engages said feed-bar, or a projection thereon, to lift said bar, and a rotating cam by which the other of said arms 120 is engaged.

8. The combination with the feed-bar F having the lug f⁶, the adjustable screw f⁵ tapped in said lug, the feed-lifting rock-shaft I having the arms i and i', the former engaging 125 said screw, and the rotating cam by which said rock-shaft is operated.

9. The combination with the feed-bar F,

of the arm f^8 the screw f^9 by which said arm is attached to said bar and on the shank of which said arm is pivoted so that its outer end may be raised or lowered when the screw is loosened, and the spring f^7 attached at its upper end to said arm, and at its lower end to some relatively stationary part; whereby by raising or lowering the outer end of said arm the tension of said spring may be varied.

10. In a sewing-machine, the combination with the bracket-arm thereof, of the swinging needle-bar frame E pivoted thereto, the needle-bar reciprocating vertically in said frame, the rock-shaft e^2 having the arms e' and e^3 , a grooved cam by which the said arm e^3 is engaged, and a link connecting the said arm e' with the said swinging needle-bar frame.

11. The combination with the rock-shaft e^2 provided with the arm e' having the curved slot e^4 , of the swinging needle-bar frame, and the link e attached at one end to said needle-bar frame and adjustably secured at its other end to the said arm e' , whereby the throw of said frame may be varied without changing its central position.

12. The combination with the rock-shaft e^2 having the arm e' , of the swinging needle-bar frame, the link e attached at one end to said rock-shaft and adjustably connected at its opposite end with the said needle-bar frame, whereby the position of the latter may be adjusted without changing its throw.

13. The combination with the rock-shaft e^2 having the arm e' , of the swinging needle-bar frame having the lug or projection e^{11} , the link e attached at one end to said arm and having at its opposite end the stud or bolt e^9 , and the screw stud or bolt e^8 the head of which is attached to the said stud or bolt e^9 and the threaded shank of which is provided with the jam-nuts e^{12} , the positions of which, on said shank, may be varied, thereby forming an adjustable connection between the said link and needle-bar frame.

14. In a sewing-machine, the combination with the presser-foot and presser-bar and a spring for depressing the same, said presser-foot having a projection, of the presser-foot-lifting rock-shaft M having at its forward end the arm m arranged to be engaged by said projection and provided at its rear end with the arm m' ; and a cam to engage said arm m' and thus impart a vertical movement to said presser bar and foot.

15. In a sewing-machine, the combination with the presser-bar having the arm k' , the presser-foot, and the screw k^2 tapped through said arm, of the rock-shaft M having the arm m arranged to be engaged by said screw to normally hold the presser-foot slightly above the work-plate, and means for operating said rock-shaft to lift the presser-foot higher at intervals.

16. In a sewing-machine, the combination 65 with the presser-foot and presser-bar and a spring for depressing the same, of a stop serving to hold said foot slightly above said work-plate during the stitching operation of the machine, said stop being vertically adjustable so that the interval between said foot and work-plate may be varied.

17. In a sewing-machine, the combination with the presser-foot and presser-bar, a spring for depressing the same and an automatic lifting device for mechanically raising said foot at intervals, of a stop serving to hold the said foot slightly above said work-plate during the stitching operation of the machine, said stop being vertically adjustable so that the space or interval between said foot and work-plate, may be varied.

18. In a sewing-machine, the combination with a presser-foot having at its forward end, in front of the needle, a rearwardly-tapering 85 opening or recess, of a presser-bar by which said foot is carried, a spring for depressing said bar, a laterally-moving needle-bar and needle, a swinging frame in which said needle-bar reciprocates vertically, and a stationary 90 overhanging bracket-arm at the forward end of which said swinging needle-bar frame is supported.

19. In a sewing-machine, a throat-plate having at its forward end in front of the needle a rearwardly-tapering opening or recess 95 the walls of which have sharp corners to form scraping or uncurling edges.

20. In a sewing-machine, the combination with a presser-foot having a rearwardly-tapering opening or recess at its forward end in front of the needle, and means for normally holding said presser-foot slightly above the work-plate, of a throat or work plate also having a rearwardly-tapering opening or recess in front of the needle.

21. In a sewing-machine, the combination with a presser-foot having a rearwardly-tapering opening or recess at its forward end, of means for holding said presser-foot slightly 110 above the work-plate during the stitching operation of the machine.

22. In a sewing-machine, the combination with a presser-foot having a rearwardly-tapering opening or recess at its forward end, of 115 a stop for holding said presser-foot slightly above the work-plate during the stitching operation of the machine, said stop being vertically adjustable so that the interval between said presser-foot and work-plate may 120 be varied.

23. In a sewing-machine, the combination with a hollow work-supporting arm or horn, of an upper feed or feeding-foot movable longitudinally of the said arm or horn and having 125 a heel or bearing portion rearward of the needle, a throat-plate having a needle-opening, a horizontally-movable needle reciprocating

crosswise of the said arm or horn, above the latter, coöperating stitch-forming devices within the said arm or horn, and a presser-foot having a rearwardly-tapering opening or recess which is arranged centrally in front of the said needle-opening in the throat-plate.

24. In a sewing-machine, the combination with a hollow work-supporting arm or horn, of an upper feed or feeding-foot moving lengthwise of the said arm or horn, a horizontally or laterally moving needle-bar and needle, coöperating stitch-forming mechanism within the said arm or horn, and a presser-foot and throat-plate both having rearwardly-tapering openings or recesses in front of said needle.

25. In a sewing-machine, the combination with a laterally-movable needle, its operating mechanism and complementary stitch-forming devices, of a foot and a stationary throat-plate having an inclosed opening and a horizontal tongue extending rearward past said needle in the line of the feed and on opposite sides of which said needle descends in working in its different vertical planes, said throat-plate having, immediately rearward of said opening, a bearing-surface which is on a level with the rest of the upper surface of the throat-plate and which receives the pressure of said foot.

26. In a sewing-machine, the combination with a laterally-movable needle-bar and needle and complementary stitch-forming devices, of a foot, and a throat-plate having a tongue extending past or rearward of the needle and on opposite sides of which said needle descends in working in its different vertical planes, said throat-plate having an inclosed opening rearward of said tongue to permit the stitches laid over the same to escape therefrom, and being beveled on its upper surface, as at p^4 , rearward of said opening, and the said plate having, immediately rearward of said opening, a bearing-surface which is on a level with the rest of the top of the throat-plate and which receives the pressure of said foot.

27. In a sewing-machine, the combination of a laterally-movable needle, its operating mechanism and complementary stitch-forming devices, including a member pressing against the fabric, of a stationary throat-plate having a needle-opening and rearward of said opening a surface level with the other top surface of the throat-plate and supporting said fabric against the pressure of said member, substantially as described.

28. In a sewing-machine, the combination with a laterally-moving needle-bar and needle and complementary stitch-forming devices, of a guiding divider or separator arranged in front of said needle and having a tongue extending rearward past the said needle, and a throat-plate also having a tongue

extending rearward past the needle, said throat-plate tongue being beneath the said divider or separator tongue.

29. In a sewing-machine, the combination with the stitch-forming devices and a foot, of a throat-plate having a rearwardly-extending tongue with needle-openings on opposite sides thereof communicating with an inclosed opening rearward of said tongue, said plate having, immediately rearward of the last-named opening, a bearing-surface which is even with the rest of the top of the throat-plate and which receives the pressure of said foot.

30. In a sewing-machine, the combination with a laterally-moving needle-bar and needle and complementary stitch-forming devices, of a divider pivoted to the horn or lower part of the machine in front of said needle and being thus adapted to be turned down out of the way when desired.

31. In a sewing-machine, the combination with a laterally-moving needle-bar and needle, complementary stitch-forming devices, and means for changing the lateral movements of said needle-bar and needle, of a foot, a stationary throat-plate having a tongue extending rearwardly past the said needle and, rearward of said tongue, an inclosed opening and the said throat-plate having, immediately rearward of said opening, a bearing-surface on which said foot rests, the said plate being detachably secured to the work-plate to permit of the use of interchangeable throat-plates having tongues of different widths, to correspond to different lateral throws of the said needle-bar and needle.

32. A sewing-machine having a member arranged to press against the fabric, and a stationary throat-plate provided with an inclosed opening and having a rearwardly-extending tongue projecting into said opening, said throat-plate having immediately rearward of said opening a surface level with the other top surface of the throat-plate and arranged to support the fabric against the pressure of said member, substantially as described.

33. In a sewing-machine, a throat or work plate rigidly secured in place and having a tongue extending rearwardly past the needle and with an opening rearward of said tongue to permit the stitches laid over the same to escape therefrom, said throat-plate having on its under side below said tongue a cross-bar rearward of the needle-openings.

34. In a sewing-machine, the combination with a hollow work-supporting arm or horn having a truncated forward end with rounded corners, of a stitch-forming mechanism consisting of a vertically and laterally reciprocating needle-bar and needle above said horn and coöperating looping devices within

said arm or horn and working close to the forward or truncated end of the latter when engaging the needle-thread, a work-plate terminating at the forward end of said horn and 5 an upper feeding-foot constructed to bear on the work rearward of the needle-hole and working lengthwise of said horn.

35. In a sewing-machine, the combination with a hollow work-supporting arm or horn 10 having a truncated forward end with rounded corners, of an upper feeding-foot working longitudinally of said horn, a divider or separator and a presser-foot serving to hold and even two parts or edges of fabric placed edge 15 to edge beneath the same.

36. In a sewing-machine, the combination with a needle-bar, needle and stationary shuttle, of a vibrating and longitudinally-reciprocating looper-rod having side flanges, a guide-block embraced by said flanges, a stud on 20 which said block is pivoted and which has a tapered or conical portion, and a looper carried by said rod.

37. In a sewing-machine, the combination 25 with a presser-foot and a presser-bar by which said foot is carried, of a rigid overhanging arm which supports said presser-bar, a laterally-swinging needle-bar frame also supported at the forward end of said rigid 30 arm, a needle-bar reciprocating vertically in said frame, a needle carried by said bar, and a vertical divider or separator in front of said needle and midway of its lateral movements.

38. In a sewing-machine, the combination 35 with a throat-plate having a needle-hole, of a rigid overhanging arm, a presser-bar supported by said arm, a presser-foot carried by said bar and having a rearwardly-tapering opening or recess central in front of said needle-hole, a horizontally or laterally reciprocating needle-bar and needle also supported by said rigid arm, and complementary stitch-forming devices co-operating with said needle.

39. In a sewing-machine, the combination 45 with stitch-forming mechanism adapted to lay threads transversely to the edges of fabrics, of a guiding divider or separator extending in the line of the feed centrally of the stitches and in front of the sewing-point, and 50 of greater dimension in front of the sewing-point longitudinally of the seam than transversely to the seam, substantially as described.

40. In a sewing-machine, the combination 55 with stitch-forming mechanism adapted to lay threads transversely to the edges of fabrics, of a guiding divider or separator extending in the line of the feed centrally of the stitches and in front of the sewing-point, and 60 of greater dimension in front of the sewing-point longitudinally of the seam than transversely to the seam and formed with parallel sides in front of the sewing-point, substantially as described.

65. 41. In a sewing-machine, the combination

with stitch-forming mechanism adapted to lay threads transversely to the edges of fabrics, of a guiding divider or separator extending below the normal plane of the upper face of the fabrics and in front of the sewing-point, and of greater dimension in front of the sewing-point longitudinally of the seam than transversely to the seam, substantially as described. 70

42. In a sewing-machine, the combination 75 with stitch-forming mechanism adapted to lay threads transversely to the edges of fabrics, of a guiding divider or separator extending in the line of the feed centrally of the stitches and in front of the sewing-point, and 80 of greater dimension in front of the sewing-point longitudinally of the seam than transversely to the seam, and uncurling devices above the work for smoothing out the edges of fabrics to be united edge to edge, substantially 85 as described.

43. In a sewing-machine, the combination 90 with stitch-forming mechanism adapted to lay threads transversely to the edges of fabrics, of a guiding divider or separator extending in the line of the feed centrally of the stitches, and in front of the sewing-point, and of greater dimension in front of the sewing-point longitudinally of the seam than transversely to the seam, and upper and lower uncurling devices for smoothing out the edges of fabrics to be united edge to edge, substantially 95 as described.

44. In a sewing-machine, the combination 100 with stitch-forming mechanism adapted to lay threads transversely to the edges of fabrics, and a presser-foot adapted to press upon the upper face of the fabrics, of a guiding divider or separator extending below the under face of the presser-foot and extending in the 105 line of the feed centrally of the stitches and in front of the sewing-point, and of greater dimension in front of the sewing-point longitudinally of the seam than transversely to the seam, substantially as described. 110

45. In a sewing-machine, the combination 115 with a laterally-moving needle-bar and needle and complementary stitch-forming devices adapted to lay threads transversely to the abutting edges of fabrics, of a guiding divider or separator extending in the line of the feed centrally of the needle movement and in front of said needle and of greater dimension in front of said needle longitudinally of the seam than transversely to the seam, substantially 120 as described.

46. In a sewing-machine, the combination 125 with stitch-forming mechanism adapted to lay threads transversely to the edges of fabrics and a presser-foot, of a guiding divider or separator extending in the line of the feed centrally of the stitches and substantially from the front edge of the bearing-surface of the presser-foot to the sewing-point, substantially 130 as described.

47. In a sewing-machine, the combination with stitch-forming mechanism adapted to lay threads transversely to and unite the edges of fabrics, of a separator arranged to extend between the edges of two fabrics to be united and separate said edges at the sewing-point, substantially as described.

In testimony whereof I affix my signature in presence of two witnesses.

SATTERLEE ARNOLD.
